UNITED STATES PATENT OFFICE

2,049,308

CONTROL OF ELECTRIC CIRCUITS

John H. Miles, Decatur, Ga., assignor to General
Electric Company, a corporation of New York

Application August 5, 1933, Serial No. 683,772

11 Claims. (Cl. 175—294)

My invention relates to improvements in the control of electric circuits and more particularly to improvements in arrangements for effecting as quickly as possible the reclosing of a circuit breaker which has opened in response to a faulty circuit condition. More especially, my invention relates to improvements in circuit controlling devices of the type disclosed in United States Letters Patent 1,658,695, issued February 10, 1928.

It has been found that, in a very large percentage of the faults which occur on power systems, the arc extinction and the de-ionization of the arc path occur so rapidly that instead of waiting some relatively long time, for example fifteen seconds, before making the first reclosure of the circuit breakers which opened in response to the fault, it is preferable to make the first reclosure as quickly as possible or substantially immediately in order better to advance the much desired continuity of service. One object of my invention is to provide a relatively simple arrangement for effecting a substantially instantaneous initial reclosure. Instantaneous initial reclosure is now understood by the art to mean no time delay in energizing the circuit breaker closing control device after the circuit breaker auxiliary switches have made contact in the open position of the circuit breaker. Another object of my invention is to provide a relatively simple and economical construction for so modifying devices such as disclosed in the patent mentioned and especially those now in service that they are readily adaptable to circuit breaker reclosing arrangements wherein an instantaneous first reclosure is desired. Further objects of my invention will hereinafter appear.

My invention will be better understood from the following description when considered in connection with the accompanying drawing and its scope will be pointed out in the appended claims.

The single figure of the accompanying drawing illustrates in perspective an embodiment of my invention and shows diagrammatically an application thereof in a reclosing circuit breaker control system.

The circuit controlling device chosen to illustrate my invention comprises two pairs of relatively movable cooperating contacts 1, 2 and 3, 4 respectively and means comprising a plurality of spaced circuit controlling members 5, 6, and 7 movable in the direction indicated by the arrow 8 by any suitable means, such as a motor 9, successively to effect circuit controlling operations of the contacts 1, 2 and 3, 4. For controlling the

movement of the members 5, 6, and 7 there is provided means, such as an electromagnet 10 whose armature 11, while in the unattracted position, permits the members 5, 6, and 7 to be held in a predetermined position illustrated in the drawing and, when in the attracted position, to permit the motor 9 to move the members 5, 6, and 7 from the predetermined position in the direction indicated by the arrow 8 so as to actuate the contacts 1, 2, and 3, 4 and not to allow further movement of the members until returned to the unattracted position.

The circuit controlling members 5, 6, and 7 may be mounted on operating members illustrated as radially disposed arms 12, 13, and 14 of a suitably mounted rotatable member such as a shaft 15 to which is secured a gear 16 of a reducing gear train 17 arranged to be driven by the motor 9. For varying the spacing of the arms 12, 13, and 14 so as to obtain the desired intervals between the actuation of the contacts, the arms are adjustably positioned on the shaft 15 by any suitable clamping means such as a nut 18 and a washer 19. It will be obvious to those skilled in the art that the gear 16 may be suitably graduated, as shown in the patent mentioned, for positioning the arms 12, 13 and 14 according to the time action desired.

For controlling the movement of the circuit controlling members 5, 6 and 7 by the motor 9 which may be continuously energized, the armature 11 of the electromagnet 10 may normally be in the unattracted position as shown. In this position it is arranged to control the movement of a brake catch 20 which is pivoted at 21 in a trunnioned yoke member 22 and biased by a spring 23 to the position shown in the drawing. In this position the brake catch 20 is engaged by a normal stop arm 24 on the shaft 15. The torque of the motor 9 as transmitted through the shaft 15 to the brake catch 20 tends to turn the yoke 22 counter-clockwise about its pivot 25 and thereby to turn a brake arm 26 also mounted on the yoke 22 in a direction to have its braking surface 27 engage the rotor 28 of the motor 9. In this way the motor 9 stalls itself to hold the parts positioned as shown in the drawing.

When the electromagnet 10 is energized and the armature 11 thereby moved to the attracted position, the brake catch 20 is released from the stop arm 24. Upon the release of the brake catch, the brake 27 is moved away from the rotor 28 by the brake release spring 29 so that the motor is free to turn the shaft 15 and the arms 12, 13, and 14 associated therewith at a

- rate dependent on the speed of the motor. For uniformity in time delay action the motor 8 is preferably a substantially constant speed motor. As the arms 12, 13 and 14 are rotated, each, through its associated circuit controlling member 5, 6, and 7, actuates the contacts 1, 2 and 3, 4 once at intervals dependent on the spacing of the arms. For reclosing circuit breaker operation these intervals may progressively increase.
- 10 In accordance with my invention, however, the contact controlling action of the contact controlling member 5 is such that the initial reclosure of the circuit breaker is made as quickly as possible after the circuit breaker opens. For this purpose the circuit controlling member 5 is mounted for movement relatively to the operating member or arm 12 and I provide restraining means for holding the contact controlling member 5 under a bias in an initial position such that the contacts 1, 2 are closed and the contacts 3, 4 open. The restraining means is indicated as a stop 38 which engages a projection 31 on the circuit controlling member 5. The circuit controlling member 5 may be pivotally mounted on the operating member 12 at 32, as shown. The bias may be provided by any suitable means, such as the spring 33, in which energy is stored during a predetermined movement of the operating member 12 while the restraining means is in the path of movement of the circuit controlling member 5. The spring 33 may interconnect the operating member 12 and the circuit controlling member 5, as shown. For convenience in operation, the restraining stop 38 may be secured to a spring-biased arm 34 which is under the control of an electromagnet 35 in such a way that the movement of the armature 36 of this electromagnet to the attracted position releases the stop 38 from the pin 31.
- 40 In order that the actuation of the contacts 1, 2 and 3, 4 may be effected positively with a minimum load on the motor, they are mounted on pivots 37, 38 and arranged to provide a hammer blow action on closure. For this purpose the free ends of the contacts 1 and 3 are mounted for lost motion and supported by any suitable means, such as a rest 39, and in turn the free ends of contacts 2 and 4 are supported by any suitable means, such as flanges 40, 41 so that if one of the contact controlling members moves toward the contacts it first engages and moves a pair of contacts, for example 1 and 2, simultaneously upward and subsequently releases contact 1 and engages and moves contact 2 towards contact 1 thereby insuring a good contact closure.
- 45 In order to have a time displacement between the circuit controlling actions of the contacts 1 and 2 and the contacts 3 and 4 the contact controlling members 5, 6, and 7 may be provided with contact moving portions 42 and 43 set at different angles. In accordance with my invention I so arrange the cycle of operation that when the stop arm 24 engages the brake catch 28 and applies the brake 27 to the motor 8, the circuit controlling member 5 is under bias of the spring 33 with the contacts 1 and 2 closed and the contacts 3 and 4 open so that immediately upon the release of the restraining member 38 the energy stored in the spring 33 moves the contact controlling member 5 in the direction indicated by the arrow 8 quickly to release the contact 2 and thereby separate the contacts 1 and 2 and almost immediately thereafter to

raise the contact 4 and drop the contact 3, thereby closing contacts 3 and 4.

For further controlling the movement of the circuit controlling members 5, 6, and 7, the shaft 15 may be provided with a lockout stop arm 44 which is angularly displaced with reference to the stop arm 24 in the direction of rotation indicated by the arrow 8 so as to permit somewhat less than one revolution of the shaft 15 before it is brought to a stop provided the armature 11 of the electromagnet 10 is in its attracted position. If this armature is in its attracted position, the lockout stop arm 44 engages the brake catch 28 and applies the brake 27 to the motor 8 so as to stop all action and lock out the device. In this way it is possible to suspend automatic operation of the device even though the electromagnet 10 be deenergized after the brake catch 28 has been moved into the path of the stop arm 44 because the torque of the motor will hold the stop 44 against the brake catch 28. The brake catch 28 may, however, be released at any time by moving the armature to the unattracted position, for example pushing on the rod 45.

25 In order more clearly to set forth the operation of the illustrated embodiment of my invention, I have shown diagrammatically an application thereof for reclosing a latched-in type of circuit breaker 46 which is arranged to control a line circuit 47 connected to a bus 48 and to be opened in response to a predetermined abnormal condition by any suitable protective means indicated as a current trip coil 49. The circuit breaker 46 may be provided with any suitable closing means, such as the closing coil 50, the circuit of which is normally open and arranged to be closed upon actuation of a control device 51. The circuit breaker is also provided with suitable auxiliary switches 52 and 53 which are arranged to be open when the circuit breaker is closed and vice versa.

50 The motor 8 may be energized from any suitable source indicated as a potential transformer 54 connected to the bus 48. The electromagnets 10 and 35, the control device or relay 51 and the closing coil 50 may be energized from any suitable source indicated as a bus 55.

Assuming that the parts are positioned as shown in the drawing, and that something happens on the circuit 47 to cause the actuation of the tripping means 49, the circuit breaker 46 will be tripped and moved to the circuit opening position. In so doing the circuit of the release magnet 10 is completed through the circuit breaker auxiliary switch 53 as follows: From one side of the bus 55, through conductor 56, auxiliary switch 53, conductor 57, resistance 58, the winding of the electromagnet 10 and conductor 59 to the other side of the bus 55. As soon as the electromagnet 10 is energized, its armature 11 is attracted to release the brake catch 28 and thereby the brake 27 so that the motor 8 is free to effect movement of the shaft 15. At the time the magnet 10 is energized, the circuit of the auxiliary electromagnet 35 is also completed through the auxiliary switch 53 as follows: From one side of the bus 55, conductor 56, switch 53, conductor 57, resistance 58, conductor 61, the winding of the electromagnet 35, conductor 62, contacts 2 and 1 of the timing device and conductor 63 to the other side of the bus 55. When the auxiliary magnet is energized, it seals itself in by its contacts 64 through conductors 65 and 66. Also, as soon as the electromagnet 35 is

energized, it moves the spring-biased arm 34 to release the restraining means 38 from the circuit controlling member 5. The energy stored in the spring 33 thereupon effects immediate movement of the circuit controlling member 5 to cause the opening of the contacts 1, 2 and the closing of the contacts 3, 4.

The closing of the contacts 3, 4 completes the circuit of the control relay 51 from one side of the bus 55, through conductor 56, auxiliary switch 53, conductor 66, control relay 51, contacts 3, 4 of the timing device, conductor 62, contacts 64 of the auxiliary magnet or relay 35, and conductors 65 and 59 to the other side of the control bus. When the control relay 51 closes its contacts, it completes a circuit from one side of the control bus 55 through its contacts, conductor 67, auxiliary switch 52, closing coil 50 and conductor 56 to the other side of the control bus thereby effecting the closing of the circuit breaker. Upon the closing of the circuit breaker, the electromagnets 10 and 35 and the control relay 51 are deenergized as a result of the opening of their circuits by the auxiliary switches 52 and 53.

If the circuit breaker 46 stays closed, the armatures of the electromagnets 10 and 35 will return to the positions shown in the drawing and the shaft 15 will rotate around into the position shown, whereupon the stop arm 24 engages the brake catch 20 to stop the motor 9. If, however, the circuit breaker 46 opens before the stop arm 24 engages the brake catch 20, it will be reclosed one or more times depending upon how soon and how often it reopens. For example, if it were to reopen immediately, it would stay open until such time as the circuit controlling member 6 was turned around in a position to actuate the contacts 1, 2 and 3, 4, whereupon the breaker would again be reclosed. If it were to open a third time, then, in due course of time, it would be reclosed by the action of the circuit controlling member 7 on the contacts 1, 2 and 3, 4. If it remains closed on any one of the first three openings, the shaft 15 will return to the position shown in the drawing and the control device will be in position for another automatic operation. If, however, after the third reclosure the circuit breaker opens immediately, the brake catch 20 will be in the path of movement of the lockout arm 44. In this case the motor 9 will be stopped and no further reclosures can take place until the brake catch 20 is released by pushing on the rod 45.

While I have shown and described my invention in considerable detail, I do not desire to be limited to the exact arrangement shown but seek to cover in the appended claims all those modifications which fall within the true spirit and scope of my invention.

What I claim as new and desire to secure by Letters Patent of the United States, is:

1. A circuit controlling device including a rotatable operating member, a circuit controlling member pivotally mounted on said operating

member for rotation relative thereto, restraining means in the path of movement of the circuit controlling member for effecting movement thereof relatively to the operating member during a definite angular movement thereof, means in

which energy is stored when the operating member is rotated while the circuit controlling member is restrained, means for stopping said operating member at the end of said definite angular movement, means for releasing said restraining means

and relatively movable cooperating contacts con-

structed and arranged to be actuated from one circuit controlling position to another by the movement of the circuit controlling member in response to the release of the energy stored in said energy storing means when said restraining means is released.

2. A circuit controlling device including relatively movable operating and circuit controlling members, restraining means in the path of movement of the circuit controlling member for effecting movement thereof relatively to the operating member during a definite movement thereof, means in which energy is stored when the operating member is moved while the circuit controlling member is restrained, means for stopping said operating member at the end of said definite movement, means for releasing said restraining means and relatively movable cooperating contacts constructed and arranged to be actuated from one circuit controlling position to another by the movement of the circuit controlling member in response to the release of the energy stored in said energy storing means when said restraining means is released.

3. A circuit controlling device including relatively movable operating and circuit controlling members, a stop in the path of movement of the circuit controlling member for effecting movement thereof relatively to the operating member during a definite movement thereof, resilient means interconnecting said members and adapted to store energy when the operating member is moved while the circuit controlling member is held by said stop, means for stopping said operating member at the end of said definite movement, electromagnetic means for releasing said stop and relatively movable cooperating contacts constructed and arranged to be actuated from one circuit controlling position to another by the movement of the circuit controlling member in response to the release of the energy stored in said resilient means when said stop is released.

4. A circuit controlling device including a rotatably mounted operating member, a contact controlling member pivotally mounted on said operating member for movement relatively thereto, restraining means in the path of movement of said circuit controlling member for effecting movement thereof relatively to the operating member during a definite angular movement thereof, means interconnecting said members and adapted to store energy when the operating member is rotated in one direction while the contact controlling member is restrained, means for stopping said operating member at the end of said definite angular movement, means for releasing said restraining means and relatively movable cooperating contacts constructed and arranged to be actuated from one circuit controlling position to another by the movement of the circuit controlling member in response to the release of the energy stored in said interconnecting means when said restraining means is released.

5. A circuit controlling device including a rotatably mounted operating member, a contact controlling member pivotally mounted on said operating member for movement relatively thereto, a stop in the path of movement of said circuit controlling member for effecting movement thereof relatively to the operating member during a definite angular movement thereof, a spring interconnecting said members and adapted to store energy when the operating member is rotated in one direction while the contact con-

- trolling member is engaged by said stop, means for stopping said operating member at the end of said definite angular movement, electromagnetic means for releasing said stop and relatively movable cooperating contacts constructed and arranged to be actuated from one circuit controlling position to another by the movement of the circuit controlling member in response to the release of the energy stored in said spring when said stop is released.
6. In combination, an electric circuit, a circuit breaker for controlling said circuit, means for effecting the opening of said circuit breaker on the occurrence of a fault on the circuit and means for effecting a substantially immediate reclosure of said circuit breaker including an operating member, a circuit controlling member, means for biasing the circuit controlling member for movement in one direction when the operating member is actuated, means for restraining said circuit controlling member in one position against its bias, means responsive to the opening of the circuit breaker for releasing said restraining means whereby said circuit controlling member can move under its bias and means controlled by the movement of said circuit controlling member for effecting the closing of the circuit breaker.
7. In combination, an electric circuit, a circuit breaker for controlling said circuit, means for effecting the opening of said circuit breaker on the occurrence of a fault on the circuit and means for effecting a substantially immediate reclosure of said circuit breaker including an operating member, a circuit controlling member, means for biasing the circuit controlling member for movement in one direction when the operating member is actuated, means for restraining said circuit controlling member in one position against its bias, means responsive to the opening of the circuit breaker for releasing said restraining means whereby said circuit controlling member can move under its bias, means controlled by the movement of said circuit controlling member for effecting the closing of the circuit breaker and means controlled by said circuit breaker when it opens for effecting the return of said circuit controlling member to its restrained position.
8. In combination, an electric circuit, a circuit breakers for controlling said circuit, means for effecting the opening of said circuit breaker on the occurrence of a fault on the circuit and means for effecting a substantially immediate reclosure of said circuit breaker including relatively movable operating and circuit controlling members, means for biasing the circuit controlling member for movement in one direction when the operating member is actuated, means for restraining said circuit controlling member in one position against its bias, means responsive to the opening of the circuit breaker for releasing said restraining means whereby said circuit controlling member can move under its bias and means controlled by the movement of said circuit controlling member for effecting the closing of the circuit breaker, means for effecting at least one subsequent reclosure when the circuit breaker opens again within a given time interval, means controlled by said circuit breaker when it opens the first time to effect the return of the circuit controlling member to its restrained position and means for preventing the return of said circuit

controlling member to its restrained position when the circuit breaker opens more than a predetermined number of times in said interval.

9. In combination, an electric circuit, a circuit breaker for controlling said circuit, means for effecting the opening of said circuit breaker on the occurrence of a fault on the circuit and means for effecting a substantially immediate reclosure of said circuit breaker including relatively movable operating and circuit controlling members, means for biasing said circuit controlling member for movement in one direction when the operating member is actuated, means for restraining the circuit controlling member in one position against its bias, means for actuating said operating member, means for stopping said actuating means at a predetermined point of movement of the operating member, means operative when the circuit breaker opens to release said restraining means and relatively movable cooperating contacts arranged to be actuated from one circuit controlling position to another to effect closure of the circuit breaker in response to the release of said circuit controlling member when the restraining means is released in response to the opening of the circuit breaker.

10. In combination, an electric circuit, a circuit breaker for controlling said circuit, means for effecting the opening of said circuit breaker on the occurrence of a fault on the circuit and means for effecting a substantially immediate reclosure of said circuit breaker including an operating member, a circuit controlling member movable relatively to said operating member, means for effecting movement of said operating member, restraining means in the path of movement of said circuit controlling member for effecting movement thereof relatively to said operating member during a predetermined part of the movement thereof, means in which energy is stored when the operating member is moved while the circuit controlling member is restrained, means for stopping said operating member at the end of said predetermined movement, means operative when the circuit breaker opens to release said restraining means and said stopping means and relatively movable cooperating contacts arranged to be actuated from one circuit controlling position to another to effect the closure of the circuit breaker in response to the release of the energy stored in said energy storing means when said restraining means is released in response to the opening of the circuit breaker.

11. A circuit controlling device including relatively movable operating and circuit controlling members, restraining means in the path of movement of the circuit controlling member for effecting movement thereof relatively to the operating member during a definite movement thereof, means for biasing said circuit controlling member for movement from its restrained position, means for stopping said operating member at the end of said definite movement, means for releasing said restraining means, and relatively movable cooperating contacts constructed and arranged to be actuated from one circuit controlling position to another by the movement of the circuit controlling member under its bias when said restraining means is released.
